(57) **CLAIM**

The ornamental design for a rugged electronic control unit housing, as shown and described.

DESCRIPTION

FIG. 1 is a top, rear, right side perspective view of an embodiment of a rugged electronic control unit housing; FIG. 2 is a bottom, front, left side perspective view thereof; FIG. 3 is a left side elevation view thereof; FIG. 4 is a front elevation view thereof; FIG. 5 is a right side elevation view thereof; FIG. 6 is a rear elevation view thereof; FIG. 7 is a top plan view thereof; and, FIG. 8 is a bottom plan view thereof.

The evenly spaced broken lines and areas within them depict portions of the rugged electronic control unit housing that form no part of the claimed design.

1 Claim, 6 Drawing Sheets
